(57) **CLAIM**

The ornamental design for a portion of a charging device, as shown and described.

DESCRIPTION

FIG. 1 is a front view portion of a charging device;
FIG. 2 is a top view thereof;
FIG. 3 is a perspective view thereof;
FIG. 4 is a cross-sectional view taken along the lines 4—4 of FIG. 1; and,
FIG. 5 is a cross-sectional view taken along the lines 5—5 of FIG. 2.
The broken line showing is for illustrative purposes only and forms no part of the claimed design.
